UNITED STATES PATENT OFFICE.

LUDWIG SEVERIN, OF HAGEN-DELSTERN, GERMANY.

PROCESS AND APPARATUS FOR THE MANUFACTURE OF INCANDESCENT MANTLES FOR INVERTED INCANDESCENT LIGHTING.

1,411,459.

Specification of Letters Patent.

Patented Apr. 4, 1922.

Application filed April 6, 1914. Serial No. 829,922.

(GRANTED UNDER THE PROVISIONS OF THE ACT OF MARCH 3, 1921, 41 STAT. L., 1313.)

To all whom it may concern:

Be it known that I, LUDWIG SEVERIN, a subject of the German Emperor, residing at Hagen-Delstern, Prussia, Germany, have invented certain new and useful Improvements in Processes and Apparatus for the Manufacture of Incandescent Mantles for Inverted Incandescent Lighting, of which the following is a specification.

10 The object of the present invention is to simplify the production, on a large scale, of incandescent mantles, provided with a supporting ring of magnesia or the like, for inverted incandescent lighting.

15 For this purpose, according to my invention, the process is as follows. The piece of material or blank or fabric, which has already been impregnated, is drawn by means of a mandrel into a corresponding

20 die or mould and converted into the desired bag-shape or cup shape having an elongated approximately cylindrical body and a convex bottom. It is then connected with the supporting ring, which is fitted in the opening

25 of the bag, by means of thread which is wound round on the outside, and is finally withdrawn from the die by means of said ring.

In carrying out the above process, one 30 may either proceed as follows. After the shaping of the piece of material by means of a mandrel of the same diameter as the incandescent mantle, first withdraw the mandrel and then introduce the supporting 35 ring into the opening of the bag, in order to connect both parts by means of a thread wound round them on the outside, or, by using a mandrel of smaller diameter one may carry out the process in such a way that 40 in shaping the piece of material the mandrel passes through the supporting ring and the material is drawn through the small annular space between the edges of the die and of the supporting ring and the connection 45 takes place on the egress side of the die. As in this latter modification of the process the diameter of the mandrel must be considerably smaller than that of the mantle, in some circumstances special precautions 50 may also be necessary, in order to prevent the formation of folds during the shaping of the incandescent mantle. These precau-

tions can, for example, consist in blowing out the mantle by means of a current of air while it is being shaped, or the head 55 of the mandrel may be subsequently enlarged in any suitable manner.

The material from which the incandescent mantle is to be formed may advantageously consist of a knitted fabric, in some cases 60 however, a woven or braided fabric may be used, and a material of which the size of the mesh is larger at the edges than in the middle may conveniently be employed. It is thus effected that during the shaping 65 of the incandescent mantle a too great accumulation of material or formation of folds at the suspension edge is avoided. It is suitable to choose the width of the mesh of the material to be so much greater at 70 the edges that, during its conversion in to the desired bag-shape only a small accumulation of material occurs in comparison with the bottom of the mantle and thus the suspension edge, on which most depends, is ad- 75 vantageously strengthened, without how- ever the formation of folds or a too great accumulation of material taking place.

The shaping of the incandescent mantle may be done equally well when the piece of 80 material is in a dry as when in a damp condition. The following is however an advan- tageous method. The material is introduced into the die in a damp condition, is dried in the die and then withdrawn from it. In 85 this way a particularly good and durable form of mantle is obtained.

In every case one obtains in a simple manner a finished impregnated incandescent mantle connected to its supporting ring. 90

Several methods of carrying out the process are illustrated, by way of example, in the accompanying drawings together with apparatus suitable for use in each case.

Figs. 1-4 illustrate the process when using 95 a mandrel of the same diameter as the incandescent mantle and employing a cylindrical socket as the die.

Figs. 5-7 illustrate the same process when using a ring as the die. 100

Fig. 8 shows a piece of material with meshes increasing in size towards the edges, suitable for the manufacture of incandescent mantles.

Figs. 9 and 10 illustrate the process when using a rigid mandrel which can be passed through the supporting ring.

Figs. 11 and 12 show the process when using a mandrel of variable diameter.

In Figs. 1-4 *a* is a cylindrical die or socket, the upper opening of which forms the shaping aperture for producing the incandescent mantle, and *b* is a mandrel fitting 10 into this opening. In manufacturing the mantle a flat or nearly flat piece of material *c*, impregnated with the luminous or incandescent medium, and of suitable size is placed on the die *a* as shown in Fig. 1, in 15 either a dry or a damp condition. The material consists preferably of knitted fabric but may in some cases be of woven or braided fabric. Then, as may be seen from Fig. 2, the material is pressed into the cylindrical die by means of the mandrel *b*, and edges *c*¹ projecting upwards are drawn tight 20 in the direction of and also at right angles to the mandrel, so that the meshes of the knitted fabric lying around the mandrel 25 are drawn lengthways and thereby any lateral folds, if present, are removed. After the material has already thus been brought substantially to the shape desired, the mandrel is withdrawn and the magnesium ring 30 *d*, to which the mantle is subsequently fastened, is set in place in the upper edge of the mantle, as is shown in Fig. 3. Then the mantle is fastened to the magnesia ring by means of a thread *f* of asbestos or other 35 heat resisting material, which is wound round it, and is drawn out of the mould or socket *a* by means of said ring. After the mantle has been withdrawn from the die its sides arch outwards somewhat in conse- 40 quence of their elasticity, so that the mantle automatically assumes by radial expansion and longitudinal contraction the convex cup shape desired, as shown in Fig. 4 for the following incineration and hardening and 45 retains this shape.

When using materials in a damp condition they are subjected to a drying process after shaping by which means an increased permanency of shape is given to the incandescent mantle.

The mode of carrying out the process which is illustrated in Figs. 5-7 differs from that described above firstly in that a simple ring is used instead of the cylindrical die 55 shown in Figs. 1-3. This ring *a* may suitably consist of india-rubber or other similar elastic material and the process can be suitably carried out in the following manner. First the piece of material *c* is drawn over 60 the mandrel *b* and held fast on it by the ring *a*, on account of the elasticity of said ring, in the shape shown in Fig. 5. After the mantle has been, if necessary, dried, and been held in this shape for so long a time that it 65 can retain the shape of its own accord, it is

stripped off together with the ring (Fig. 6). The width of the ring must in this case be made such that, on account of its elasticity, it causes no excessive pulling together of the mantle, so that the mantle can then be set 70 on the magnesia ring *d*, as shown in Fig. 7, and bound to it, whereupon the ring *a* is removed. The magnesia ring *d* is held fast in its position on the base *h* by means of a central mandrel *g* which projects into the opening of the ring.

Instead of the rubber ring *a*, in some cases a simple thread of ramie fibre or other material may be used. The advantage of this is that the special removal of the ring is 80 unnecessary because in the subsequent incineration the thread is simply consumed as well.

Fig. 8 shows the peculiar mesh arrangement of a piece of material. It can be distinctly seen that the width of the meshes becomes considerably larger from the centre of the material towards the outside. Thus too great an accumulation of material at the upper edge of the incandescent mantle 90 is avoided.

In the processes illustrated in Figs 9 and 10 the apparatus employed may suitably consist of a fixed shaping piece *i* having a recess *k* in its upper end, in which the supporting ring *d* is placed in an inverted position, that is, with its feet downwards. Immediately above the piece *i* a plate *m* having a circular opening is arranged. This plate can either be fitted from above over the edge of the support *d* or may advantageously consist of two halves which can slide or be adjusted laterally, and forms the shaping aperture. The mandrel *n* is vertically guided in the central bore of the shaping 100 piece *i* and its diameter is such that it can pass through the supporting ring.

In manufacturing the mantle the supporting ring *d* is first set in the upper recess *k* in the shaping piece *i* with its feet 110 downwards and the material *c* laid over it as shown in Fig. 9. Then the two halves of the shaping plate *m* are moved close together laterally and the mandrel *n* is moved upwards, so that the piece of material *c* is 115 drawn between the edge of the shaping-piece *i* and that of the ring plate *m* and is converted to the bag shape above the supporting ring *d*. The divided ring plate *m* is so arranged, that the connection-groove of the magnesia ring *d* projects slightly above it 120 and lies on the egress side of the shaping aperture, so that the fastening thread can be at once wound round from outside and the mantle be connected to the magnesia ring. 125

On account of the smaller diameter of the mandrel, the incandescent mantle does not at first assume the desired uniform dome-shape, but this results during the usual subsequent treatment (incineration, hardening and 130

the like) of its own accord. A good shape can however be at once obtained if another die or socket *o*, as shown by dotted lines in Fig. 10, is placed over the mantle and compressed 5 air blown in from below through piping not shown in the drawing, for example, by constructing the mandrel itself of hollow form, so that the mantle is blown to the shape desired.

10 The arrangement of this second die has further the great advantage that there remains a gap *p* between the die *o* and the ring plate *m* on a level with the connection groove of the magnesia ring. This gap serves as a 15 guide-passage for the introduction of the fastening thread and thus the actual fastening is considerably facilitated and the working is accelerated.

Instead of a mandrel of unalterable diameter in some cases one employs a mandrel of which the upper part can be extended in a suitable manner after being introduced into the mantle.

In the example illustrated in Figs. 11 and 25 12 the mandrel itself is formed from a simple envelope *r* which is connected with a pipe *s* for the inflow and outflow of the filling medium and provided with a net-work *t* which when expanded possesses exactly the 30 desired shape. This alterable mandrel can either be movable longitudinally as shown in Figs. 9 and 10 or may be fixed as shown in Figs. 11 and 12. In the latter case as shown in Fig. 11 the magnesia ring is placed 35 over the mandrel which is at first only slightly extended, and the mandrel is then blown up to the correct shape (Fig. 12). The piece of material is then laid over it, smoothed out and bound with the thread 40 and fastened. Finally the air is released from the extended mandrel so that this collapses and the finished mantle can be removed from above.

The mantles manufactured by the process 45 according to the invention can then be subjected to the usual further treatment, i. e. incinerated, shaped and hardened or can be put on the market as impregnated bodies.

What I claim as my invention and desire to secure by Letters Patent is:—

1. The process of making inverted gas mantles comprising molding a piece of suitably impregnated material approximately into the form of a cup between internal and external means, permitting it to take more completely by expansion the form of a cup, aiding such expansion by injection of air and tying the rim of such cup to a carrier ring.

60 2. A gas mantle blank of circular form consisting of a fabric having meshes at and near its edge considerably coarser than those in the middle.

3. In apparatus for making incandescent 65 gas mantles from suitably impregnated

pieces of fabric, the combination of a cup-like die for receiving the piece of fabric, a carrier ring arranged to press the inner part of said fabric into said die and a mandrel adapted to be inserted into said ring 70 and die for drawing the fabric between the latter two parts, the said ring being adapted to have the said fabric tied thereto before withdrawing the mantle from the die.

4. In apparatus for making incandescent 75 gas mantles from suitable impregnated pieces of fabric, the combination of a cup-like die for receiving the same, a carrier ring arranged to press the inner part of said fabric into said die, an expandable mandrel adapted to be inserted into said ring 80 and die for drawing the fabric between the latter two parts and means for expanding the mandrel, the said ring being adapted to have the said fabric tied thereto before removal from the die.

5. In apparatus for making incandescent 85 gas mantles from suitable impregnated pieces of fabric, the combination of a cup-like die for receiving the piece of fabric, a 90 carrier ring arranged to press the inner part of said fabric into said die, a mandrel adapted to be inserted into said ring and die to draw the fabric between the latter two parts and means for blowing air into the 95 fabric to expand the same into the die, the said ring being adapted to be tied to the said fabric before withdrawing the mantle from the die.

6. In apparatus for making incandescent 100 mantles from suitably impregnated pieces of fabric, the combination of a cup-like die for receiving the piece of fabric with an expandable mandrel adapted to enter said die, a carrier ring adapted to pass over said 105 mandrel while the latter is in a contracted state and means for expanding said mandrel after the ring has thus passed over it, these parts being adapted to have the fabric pressed snugly down on said mandrel and 110 ring and tied to the latter before contracting said mandrel and withdrawing the mantle.

7. In apparatus for making incandescent 115 gas mantles from suitable impregnated pieces of fabric, the combination of a die having a form corresponding to that of the mantle and expanding means adapted to pass through the carrier ring of the mantle, for pressing the fabric snugly into said die. 120

8. In apparatus for making incandescent 125 gas mantles from suitably impregnated pieces of fabric, the combination of a die having a form corresponding to that of the mantle and a mandrel, capable of being blown out and adapted to pass through the carrier ring of the mantle, for pressing the fabric snugly into said die.

9. In apparatus for making incandescent 130 gas mantles from suitably impregnated

pieces of fabric, the combination of a holder for the carrier ring, and a mandrel, capable of being blown out mounted in said holder and adapted to pass through said 5 ring, and a net surrounding said mandrel and adapted to give the latter, when blown out, the shape of the mantle.

In testimony whereof, I have signed my name to this specification in the presence of two subscribing witnesses.
